UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

LAMP FOR PROJECTING APPARATUS.

1,377,728.

Specification of Letters Patent. Patented May 10, 1921.

Application filed January 10, 1917. Serial No. 141,722.

To all whom it may concern:

Be it known that I, NICHOLAS POWER, a citizen of the United States, and a resident of Brooklyn, county of Kings, State of New York, have invented new and useful Improvements in Lamps for Projecting Apparatus, of which the following is a specification.

This invention relates to improvements in lamp supports of the character particularly adapted for use with motion picture or other projecting apparatus. The object of the invention is to provide a lamp support, preferably a support for an arc lamp, such as 10 is designed to be inclosed in a lamp-house or similar covering, in which the entire lamp structure may be brought to an accessible position for inspection, adjustment, etc., without disturbing the adjustment of the lamp 15 with regard to the optical axis and focus 20 of the condensers of the projecting mechanism.

A further object of the invention is to provide a device of this character which 25 may be readily applied to lamp structures now in use without involving a modification of the parts of the present lamp structure beyond the skill of the ordinary mechanic or repair man.

30 A further object of the invention is to provide a device of this character in which the lamp as a whole may be easily shifted from projecting position to the desired position for inspection etc., and vice versa in 35 a moment's time, to thereby avoid prolonged interruption of the exhibition.

In the accompanying drawings I have illustrated a further embodiment of my invention as applied to the well known type 40 of lamp and lamp-house now on the market, but it will be understood that the attachment may be adapted to other styles of lamps and lamp-houses and otherwise modified without departing from the spirit 45 and scope of my invention as defined in the appended claims.

In the said drawings:

Figure 1 is a longitudinal sectional view 50 of the well known type of lamp-house showing the lamp in projected position and with my improved attachment applied for permitting its ready adjustment to a more convenient and accessible position.

Fig. 2 is a plan view of the lamp base

shown in Fig. 1 and partly in section on line 2—2 of Fig. 1; and

Fig. 3 is a detail view of an attachment forming part of my invention.

Referring now to the drawings, 1 indicates a part of the projecting machine upon 60 which is supported the base 2 of the lamp-house which incloses the projecting lamp. Supported in suitable lugs projecting upwardly from the base of the lamp-house is a pair of longitudinally extending rods 3 65 constituting tracks upon which the base 4 of the lamp is mounted for movement toward and from the condensers 5 of the lamp-house.

As shown, the lamp comprises the usual 70 post 6 projecting upwardly from the base 4 and supporting the upper and lower brackets which carry the carbons 7 of the lamp, the carbons extending in inclined position 75 so that the direction of greatest illumination from the crater of the arc is toward the condensers 5.

The above described mechanism comprises the essential parts of a projecting arc as now in use, the rods 3 being long enough to permit the active ends of the carbons to be adjusted toward and from the condensers to an extent sufficient to secure the proper focus of the light under all practical conditions. In use, the location of the illuminating ends 80 of the carbon is quite near the rear wall of the condenser so that the major portion of the lamp cannot be readily reached through the doors forming the side walls of the lamp-house, one of which doors is indicated at 90

8 in Fig. 1. It not infrequently happens that slight adjustment of the members holding the carbons and other parts not provided with adjusting devices for actuation from without the lamp-house, require manipulation in order to secure the proper operation of the lamp, and it has heretofore been necessary to shut off the lamp and completely remove the superstructure of the lamp-house or else work at great inconvenience in making the necessary repairs and adjustments. 95

In carrying out my invention to overcome this difficulty, I extend the rods 3 forming the lamp-supporting tracks substantially to the rear wall of the lamp-house, and provide for effecting the adjustment of the base along the rods, a screw shaft 10 having its end threaded through a lug in the rear wall 100

of the base 4, as indicated at 11, the unthreaded portion of the shaft adjacent the handle working through a lug 12 on the base 2 of the lamp-house outside the rear wall.

5 The lug 12 is slotted to receive a latch 15 pivoted on the rear wall of the lamp-house and provided with a projecting handle by which it may be readily shifted to withdraw its end from the groove 14 formed in 10 the threaded shaft 10 adjacent its knob. A spring 16 is mounted as shown to normally hold the latch in engagement with the groove.

In operation the adjustment of the lamp 15 to the proper position with regard to the focus of the condensers is effected by rotating the screw shaft while held locked against longitudinal movement by means of the latch 15. Should it become necessary in the course 20 of the exhibition to adjust some part of the lamp which is not accessible through the door 8 of the lamp-house, the operator has merely to depress the handle of the latch and draw the entire lamp back on the track 25 rods 3 until the part to be removed or to be repaired or adjusted is opposite the door opening. After the repair or adjustment is completed, the lamp is pushed toward the condensers by means of the screw shaft and 30 without rotating the latter, until the latch again snaps into the groove 14 of the screw shaft. This will return the lamp to the exact position which it occupied before, and the exhibition may be resumed with a minimum loss of time.

In the greater number of lamp-projecting apparatus now on the market the adjustment of the lamp with regard to the focusing condensers is effected by means of a screw shaft 40 similar to the screw shaft 10 threaded in the base of the lamp in a manner similar to the arrangement shown in the drawing working through an ear on the base of the lamp-house. In applying my improvement to such 45 constructions it is only necessary to slot the ear and cut the groove 14 in the end of the shaft 10 to receive the end of the latch 15, and pivot the latch in place upon the rear wall of the lamp-house. This part may be 50 added by merely tapping a small threaded hole in the base of the lamp-house to receive the pivoted screw of the latch.

In the above description and accompanying drawings, I have disclosed an embodiment of my invention which is preferred because of its ready adaptation to the present design of lamp-house, but it will of course be understood that various other means may be employed for locking the shaft in operative position, and that various other changes may be made in the construction within the scope of my invention.

I claim:

1. In a lighting equipment for projecting

machines, the combination of a lamp, a housing therefor, means for adjusting the position of the lamp within the housing comprising a screw mechanism for effecting minute adjustments of the lamp, said screw mechanism embodying a part normally held against bodily movement, and means for releasing said part whereby the lamp and screw mechanism may be slidably shifted as a unit to permit the rapid extensive adjustment of said lamp. 65

2. In a lighting equipment for projecting apparatus, the combination of a lamp support, a screw for adjusting the lamp support to focus the light, said screw being mounted for both rotary and longitudinal movement relative to said lamp support, a bearing for said screw stationary relative to the frame of the projecting apparatus and normally maintaining said screw in fixed longitudinal relation thereto, and means for 80 releasing said screw for longitudinal movement relative to said bearing. 75

3. In a lighting equipment for projecting apparatus, the combination of a lamp-support, a screw for adjusting the lamp-support 90 to focus the light, said screw being mounted for both rotative and longitudinal movement relative to the movement of the projecting apparatus, and a latch for normally holding the screw against longitudinal movement 95 relative thereto to render its rotative movement effective for shifting the lamp, the lamp and screw being longitudinally movable as a unit for quick adjustment when said latch is released. 100

4. In a lighting equipment for projecting apparatus, the combination of a lamp-support, a screw for adjusting the lamp-support to focus the light, said screw being mounted for both rotative and longitudinal movement, a bearing for said screw on the base of the lamp-housing, a latch working in said bearing, and a groove in said screw adapted to be engaged by said latch to hold the screw against longitudinal movement in 110 fixed position with relation to said bearing. 105

5. In a lighting equipment for projecting apparatus, the combination of a lamp, a housing therefor, a screw mechanism for effecting minute adjustment of the lamp within said housing comprising a screw normally held stationary relative to the frame of the projecting apparatus, and means for releasing the screw and permitting it extensive longitudinal movement and subsequently permitting its return to the exact position occupied previous to said extensive movement. 115

Signed at New York city, in the county of New York and State of New York, this 30th 125 day of Dec., 1916.

NICHOLAS POWER.

It is hereby certified that in Letters Patent No. 1,377,728, granted May 10, 1921, upon the application of Nicholas Power, of Brooklyn, New York, for an improvement in "Lamps for Projecting Apparatus," an error appears in the printed specification requiring correction as follows: Page 2, lines 93, claim 3, for the word "movement" read *frame*; and that the said Letters Patent should be read with this correction therein that the same may conform to the record of the case in the Patent Office.

Signed and sealed this 14th day of June, A. D., 1921.

[SEAL.]

WM. A. KINNAN,

Acting Commissioner of Patents.
